UNITED STATES PATENT OFFICE.

JOSEPH LEON GOBEILLE, OF CLEVELAND, OHIO, ASSIGNOR TO THE JOLIET STOVE WORKS, OF JOLIET, ILLINOIS.

DESIGN FOR A STOVE.

SPECIFICATION forming part of Design No. 24,671, dated September 10, 1895.

Application filed August 2, 1895. Serial No. 558,025. Term of patent 3½ years.

To all whom it may concern:

Be it known that I, JOSEPH LEON GOBEILLE, a citizen of the United States, residing in Cleveland, in the county of Cuyahoga and state of Ohio, have invented and produced a new and original Design in Stoves, of which the following is a specification, reference being had to the accompanying drawings, showing a perspective view thereof.

The leading features of my design consist of the stove-base A, the central or body portion B, and the top C, all said parts ornamented as shown and described. Thus the base A has three distinct swells 1, 2, and 3 on different planes and extending entirely around the stove, and scrollwork a decorates the lower or border part 3, while separate upright ornamental figures c extend across both the rounded surfaces 1 and 2.

The central or body portion B is distinguished, especially, by plain columns 4 at its corners with small beads along their center, and said columns terminate at the base of the arches at the top of the respective sides of the stove. These arches are filled in with wicker-work 6, wrought out on curved lines to lend grace to the design, while wicker or

basket work also fills in the larger part of the sides between columns 4.

The top portion C is massive in design and swells out conspicuously at its corners, which run down to a point near the top of column 4, and the space between these corners is arched and retreating and overhangs the wicker-work 6, above described. The extreme top 10 of the portion C is relieved by a border 11 from the curved arched portion 12 beneath, and any suitable ornamental figure (indicated here by 14) may be used to surmount and complete the design.

What I claim is—

1. In a design for a stove, the base substantially as shown and described.
2. In a design for a stove, the body substantially as shown and described.
3. In a design for a stove, the top substantially as shown and described.
4. The design for a stove substantially as shown and described.

JOSEPH LEON GOBEILLE.
